[57] CLAIM

The ornamental design for a mirror, as shown and described.

DESCRIPTION

FIG. 1 is a front elevational view of a mirror showing my new design;

FIG. 2 is a right side elevational view thereof; and
FIG. 3 is a top plan view thereof.

The unshown rear of the design is substantially the same as what is shown in FIG. 1 except that the rectangular area comprising the mirror and the rectangular area above the mirror are flat plain and unornamented.

FIG. 3

FIG. 1

FIG. 2
